UNITED STATES PATENT OFFICE.

EDWARD S. STIMPSON, OF HOPEDALE, MASSACHUSETTS, ASSIGNOR TO DRAPER COMPANY,
OF HOPEDALE, MASSACHUSETTS, A CORPORATION OF MAINE.

THREAD-CUTTING TEMPLE FOR LOOMS.

No. 890,884.

Specification of Letters Patent.

Patented June 16, 1908.

Application filed August 13, 1907. Serial No. 388,318.

To all whom it may concern:

Be it known that I, EDWARD S. STIMPSON, a citizen of the United States, and resident of Hopedale, county of Worcester, State of Massachusetts, have invented an Improvement in Thread-Cutting Temples for Looms, of which the following description, in connection with the accompanying drawing, is a specification, like letters on the drawing representing like parts.

This invention relates to that type of loom-temple provided with means to cut the filling end extending from the selvage of the cloth to the replenishing mechanism in an automatic filling-replenishing loom, such a temple forming the subject-matter of United States Patent No. 585465 granted June 29, 1897 to me and another. In said patent the temple-head is provided with a fixed blade at one end of the temple-roll, and a co-operating blade is arranged to have a rocking and sliding movement, to engage the filling end and then to part the same between the cutting edges of the blades. The adjacent bearing of the roll extends beneath the carrier on which the movable blade is mounted, said carrier having a bearing on which it slides, located below the journal inside the temple-head.

Owing to wear or looseness of the parts the movement of the blade-carrier at times engages and damages the roll bearing, at the same time interfering with the proper operation of the temple.

My present invention has for one of its objects the construction of a thread-cutting temple whereby injury to the roll-bearing or the blade-carrier is completely obviated, the certainty of operation of the temple as a whole being substantially increased. I have also so constructed and arranged certain portions of the device that wear is diminished.

The various novel features of my invention will be fully described in the subjoined specification and particularly pointed out in the following claims.

Figure 1 is an end elevation of a loom temple embodying one form of my present invention, the slide-bar or shank being broken off; Fig. 2 is a top plan view of the temple; Fig. 3 is a front elevation thereof; Fig. 4 is a vertical section on the line 4—4, Fig. 3, looking toward the right.

Referring to the drawings, the temple-head comprising the pod P and cap C, the

slide-bar or shank B and depending heel B', both forming a part of the pod, may be and are substantially as in the patent referred to, the cap having mounted in its ends threaded bushings c, c' which form bearings for the journals of the toothed roll R, one of the journals r being shown in section, Fig. 4. At one end the pod is slotted at p, Fig. 3, to receive a fixed steel blade 1 having an upright cutting edge 2, the blade being located in the center of the slot. The shank B has a slot b, Fig. 4, opposite the slot p; and the lower part of the shank below the slot has an external bearing b', and in the slot b is loosely inserted the base 3 of a movable blade-carrier, upturned and extended toward the front of the temple-head, at 4.

As best shown in Fig. 4 the blade-carrier overhangs the adjacent roll-journal r and it will be seen that it extends across the top of the cap, which is flattened at c' to form a long beating upon which the under edge of the part 4 may slide. The movable blade is fixedly secured to and depends from the free end of the part 4, and preferably is made duplex, the two members 5 of said blade being rigidly secured to the blade-carrier one at each side of the fixed blade 1, see Fig. 3.

As shown in Figs. 1 and 4 the cutting edge 6 of the duplex blade 5 is diagonal, crossing the edge 2 of the fixed blade, the extremity of the blade 5 normally projecting beyond the temple-head, Figs. 1 and 4. Lugs 7 extend laterally from the lower end of the blade-carrier, to abut against the shank B at opposite sides of the slot b to limit movement of the carrier to the right, Figs. 1 and 4. Such movement is effected by a spring 8, coiled about a stud b' on the shank and having its free end s' connected with a lug 8 on a heel 9 depending from and forming a rigid continuation of the base 3 of the blade-carrier, the latter having lateral ears 10 which move upon the bearing b'. The heel 9 is normally held nearer the back of the loom than the heel B' on the pod of the temple, and when the lay beats up it first engages the heel 9 and rocks the blade-carrier, the ears 10 rocking on the under side of the bearing b' and bringing the overhanging end 4 of the carrier down upon the bearing c'. As the lay continues its forward movement the blade-carrier is moved bodily with it, the part 4 sliding upon the bearing c', as will be manifest. When such rocking and sliding

100
105
110

movement of the blade-carrier is effected after filling replenishment the blade 5 is first depressed to hook over and engage the filling end, and then the sliding movement draws 5. the cutting edge 4 across the edge 2 of the fixed blade 1, severing the thread with a shearing cut, which is very efficient and certain in action.

It will be noted that both of the bearings 10 b' and c^x are on the exterior of the temple-head, the bearing c^x being located above the roll-journal r, so that under no circumstances of wear or looseness of parts can the blade-carrier come into engagement with the journal or its bearing.

To limit the upward throw of the blade-carrier due to the stress of the spring I have attached to the top of the cap a plate 12 having an extension 13 which overhangs the free 20 end of the carrier, and serves as a limiting stop therefor. This stop is conveniently held in place by the bolt 14 which secures the cap on the pod.

The normal, or spring-induced position of 25 the movable blade and its carrier is clearly shown in Figs. 1 and 4, the said blade then being in readiness to descend and hook over and engage the filling end when required.

By making the bearing c^x long the wear on 30 the part 4 of the movable blade-carrier is reduced, and by its location outside the temple-head and above the roll-journal no damage to the latter can be effected by the blade-carrier, even if operating under abnormal conditions.

Having fully described my invention, what I claim as new and desire to secure by Letters Patent is:—

1. A loom-temple having a roll rotatably 40 mounted therein, a fixed blade at one end of the roll, a coöperating movable cutter, and a bearing for and upon which it is slidable, located above the axis of rotation of the roll and on the exterior of the temple.

45 2. A loom-temple having a pod slotted at one end, a roll, a cap, a fixed blade within the slot, a coöperating movable blade, and a

bearing upon which it is slidable, located on the top of the cap.

3. A loom-temple provided with a fixed 50 blade, a coöperating blade capable of rocking and longitudinal movements, and separate bearings for said blade, upon which it rocks and slides, respectively, both bearings being on the exterior of the temple. 55

4. A reciprocating temple provided with a fixed blade, combined with a coöperating movable blade, two separate bearings on the exterior of the temple, on which said movable blade may rock and slide, respectively, 60 and a member connected with the said blade and by or through which it is moved.

5. In a loom-temple, a head having roll-bearings at its ends, a roll journaled therein, a fixed cutting blade at one end of the roll, a 65 coöperating movable blade, a blade-carrier upturned to overhang the adjacent roll-journal, and a bearing on the top of the temple head upon which the blade-carrier is slidable to effect coöperation of the blades. 70

6. A reciprocating temple provided with a fixed blade, combined with a coöperating movable blade, two separate bearings on the exterior of the temple, on which said movable blade may rock and slide, respectively 75 a spring to normally position the movable blade, and a stop limit spring-induced movement thereof.

7. In a loom-temple, a head slotted at one end, a fixed blade in the slot, a coöperating 80 movable-blade, a blade-carrier, independent bearings on the exterior of the head, on which said blade-carrier is adapted to rock and slide, respectively, a controlling spring for the blade-carrier, and an overhanging 85 stop therefor on the head.

In testimony whereof, I have signed my name to this specification, in the presence of two subscribing witnesses.

EDWARD S. STIMPSON.

Correction in Letters Patent No. 890,884.

It is hereby certified that in Letters Patent No. 890,884, granted June 16, 1908, upon the application of Edward S. Stimpson, of Hopedale, Massachusetts, for an improvement in "Thread-Cutting Temples for Looms," an error appears in the printed specification requiring correction, as follows: In line 77, page 2, after the word "stop," the word *to* should be inserted; and that the said Letters Patent should be read with this correction therein that the same may conform to the record of the case in the Patent Office.

Signed and sealed this 30th day of June, A. D., 1908.

Acting Commissioner of Patents.

movement of the blade-carrier is effected after filling replenishment the blade 5 is first depressed to hook over and engage the filling end, and then the sliding movement draws 5. the cutting edge 4 across the edge 2 of the fixed blade 1, severing the thread with a shearing cut, which is very efficient and certain in action.

It will be noted that both of the bearings 10 b' and c^x are on the exterior of the temple-head, the bearing c^x being located above the roll-journal r, so that under no circumstances of wear or looseness of parts can the blade-carrier come into engagement with the journal or its bearing.

To limit the upward throw of the blade-carrier due to the stress of the spring I have attached to the top of the cap a plate 12 having an extension 13 which overhangs the free 20 end of the carrier, and serves as a limiting stop therefor. This stop is conveniently held in place by the bolt 14 which secures the cap on the pod.

The normal, or spring-induced position of 25 the movable blade and its carrier is clearly shown in Figs. 1 and 4, the said blade then being in readiness to descend and hook over and engage the filling end when required.

By making the bearing c^x long the wear on 30 the part 4 of the movable blade-carrier is reduced, and by its location outside the temple-head and above the roll-journal no damage to the latter can be effected by the blade-carrier, even if operating under abnormal conditions.

Having fully described my invention, what I claim as new and desire to secure by Letters Patent is:—

1. A loom-temple having a roll rotatably 40 mounted therein, a fixed blade at one end of the roll, a coöperating movable cutter, and a bearing for and upon which it is slidable, located above the axis of rotation of the roll and on the exterior of the temple.

45 2. A loom-temple having a pod slotted at one end, a roll, a cap, a fixed blade within the slot, a coöperating movable blade, and a

bearing upon which it is slidable, located on the top of the cap.

3. A loom-temple provided with a fixed 50 blade, a coöperating blade capable of rocking and longitudinal movements, and separate bearings for said blade, upon which it rocks and slides, respectively, both bearings being on the exterior of the temple. 55

4. A reciprocating temple provided with a fixed blade, combined with a coöperating movable blade, two separate bearings on the exterior of the temple, on which said movable blade may rock and slide, respectively, 60 and a member connected with the said blade and by or through which it is moved.

5. In a loom-temple, a head having roll-bearings at its ends, a roll journaled therein, a fixed cutting blade at one end of the roll, a 65 coöperating movable blade, a blade-carrier upturned to overhang the adjacent roll-journal, and a bearing on the top of the temple head upon which the blade-carrier is slidable to effect coöperation of the blades. 70

6. A reciprocating temple provided with a fixed blade, combined with a coöperating movable blade, two separate bearings on the exterior of the temple, on which said movable blade may rock and slide, respectively 75 a spring to normally position the movable blade, and a stop limit spring-induced movement thereof.

7. In a loom-temple, a head slotted at one end, a fixed blade in the slot, a coöperating 80 movable-blade, a blade-carrier, independent bearings on the exterior of the head, on which said blade-carrier is adapted to rock and slide, respectively, a controlling spring for the blade-carrier, and an overhanging 85 stop therefor on the head.

In testimony whereof, I have signed my name to this specification, in the presence of two subscribing witnesses.
